UNITED STATES PATENT OFFICE.

ROBERT ANDERSON, OF BROOKLYN, ASSIGNOR TO S. O. RIDER, OF NEW YORK, N. Y.

IMPROVEMENT IN MACHINES FOR HULLING COFFEE.

Specification forming part of Letters Patent No. 55,947, dated June 26, 1866.

To all whom it may concern:

Be it known that I, ROBERT ANDERSON, of Brooklyn, in the county of Kings and State of New York, have invented a new and useful Improvement in Machines for Hulling and Polishing Coffee; and I do hereby declare that the following is a full, clear, and exact description of the same, reference being had to the accompanying drawings, making a part of this specification, in which—

Figure 1 is a plan view of the invention in an open condition. Fig. 2 is a vertical longitudinal section of the same in a closed condition.

Similar letters of reference indicate corresponding parts in both figures.

This invention consists in a novel construction of a machine for removing the hulls and skins from coffee-berries, whereby the required hulling and polishing operations are performed in a very rapid and efficient manner.

To enable others to understand the construction and operation of my invention, I will proceed to describe it with reference to the drawings.

A represents a conical or tapering case formed of sheet metal or other suitable material and supported in a horizontal position by means of standards B. This case A is divided horizontally into two halves, which are hinged together at one side, as shown at a', so that they may be opened or swung apart, as represented in Fig. 1. Secured upon the smaller end of the case A is an annular grinder, or concave, C, of cast-iron or other material, which is also somewhat conical in form, and which has its inner surface studded with any desired number of short nodules or teeth, a, as shown more clearly in Fig. 1. Formed in the upper side of this concave C is an opening, b, to the upper end of which is fitted a hopper, c.

D is a longitudinal central shaft, one end of which works in a bearing formed in the large end e of the case A, while the opposite end thereof works in a similar bearing in the end f of the concave C. Placed in the said concave and fixed upon the end of the shaft D is a slightly conical circular block or wheel, E, which has oblique ribs g formed transversely upon its circumference, as shown more clearly in Fig. 1. The distance between the inner sides of

the concave and the circumference of the wheel E is sufficient to allow the coffee-kernels to pass between them, at the same time that they are close enough to tear or break the hulls away from the said kernels, as will be herein-after fully set forth.

Fixed upon the main length of the shaft D, within the case A, is a long tapering hub or block, F, in which are secured radial vanes or wings G, the outer edges of which are nearly or quite in contact with the sides or inner circumference of the case A, and are made of rawhide or other suitable material.

The inner sides or circumference of the case A are coated with any appropriate cement in order to give it the roughness required in order to remove the skins from the coffee-berries and to polish the said berries. Formed in the lower side of the largest end of the case A is an opening, i, at the lower side of which is fitted an outwardly-projecting spout, j. Fixed upon the outer end of the shaft D is a crank, k, by means of which the said shaft is rotated, and also secured upon the same end of the said shaft is a pulley or band-wheel, m.

H represents a fan-blower, which is operated by a belt, n, passing from the pulley m to a smaller pulley, r, on the shaft of the fan. The air-pipe s of this fan-blower is curved and situated in such relation with the spout j as to blow the hulls and refuse from the polished coffee-kernels as they pass from the machine, as will be presently further explained.

The case A being closed and a rotary motion communicated to the shaft D, the unhulled coffee-berries are placed in the hopper c and pass down through the opening b into the space between the wheel E and the concave C, whereupon the tearing and abrading action of the ribs g and teeth or nodules a tear and strip the hulls from the kernels, the mingled hulls and kernels being forced gradually inward into the case A by the oblique edges of the ribs g.

Having thus entered the case A, the kernels are acted upon by the rotating vanes G, which triturate them in contact with the rough inner surface of the case A until the skins which envelop the kernels are entirely removed and the said kernels polished by the friction upon them, which being done, the ker-

nels, together with the hulls, pass out through the opening *i* into the spout *j*, whereupon the blast of air from the fan-blower blows the hulls and refuse out and over one side of the spout *j*, while the clean and polished kernels pass off from the end thereof. The proper passage of the coffee and hulls from the small to the large end of the case *A*, or, in other words, from the hulling-mill *C E* to the opening *i*, is secured by the inclined position of the lower side of the said case *A*.

What I claim as new, and desire to secure by Letters Patent, is—

The combination, in a machine for hulling and polishing coffee, of an obliquely-ribbed wheel, *E*, rotating within a slightly conical toothed concave, *A*, constructed as described, and a series of wings, *G*, rotating within a horizontal tapering or conical case, *A*, the whole arranged to operate substantially as herein set forth, for the purpose specified.

ROBERT ANDERSON.
